UNITED STATES PATENT OFFICE.

PAUL STECK, OF OAKLAND, ASSIGNOR TO PARKE & LACY, OF SAN FRANCISCO, CALIFORNIA.

AMMONIA-CONDENSER FOR ICE-MACHINES.

SPECIFICATION forming part of Letters Patent No. 409,072, dated August 13, 1889.

Application filed October 24, 1888. Serial No. 289,062. (No model.)

To all whom it may concern.

Be it known that I, PAUL STECK, of Oakland, Alameda county, State of California, have invented an Improvement in Ammonia-5 Condensers for Ice-Machines; and I hereby declare the following to be a full, clear, and exact description of the same.

My invention relates to the class of ice-machines, and especially to the condensers 10 through which the ammonia is passed, and in which it is condensed by the water which trickles over the exterior of the pipes.

My invention consists in a novel condenser composed of separated sections or coils of 15 pipes, the lowermost pipe of each section or coil being connected with the uppermost pipe of the section or coil adjacent, an inlet for the ammonia-gas to the top pipe of the first section or coil, and an outlet for the liquid ammonia 20 from the bottom pipe of each section or coil, all of which, together with the objects of this construction, I shall hereinafter fully set forth.

Referring to the accompanying drawings for a more complete explanation of my invention, Figure 1 is a vertical cross-section 25 through the condenser. Fig. 2 is a side elevation of the same.

I have not deemed it necessary herein to show the frame or box of the ice-machine of 30 which the condenser forms a part, as the usual surroundings and operation of an ammonia-condenser in this class of machines are well known.

A is the first section or coil of pipes of the 35 condenser. B is the second, similarly constructed. C is the third, and D is the fourth section or coil. There may be as many (more or less) as may be desired.

A' is a pipe connecting the lowermost pipe 40 of the first section or coil A with the uppermost pipe of the second section or coil B.

B' is a pipe connecting the lowermost pipe of the second section or coil with the uppermost pipe of the third.

45 C' is a pipe connecting the lowermost pipe of the third with the uppermost pipe of the fourth section or coil D.

E is an inlet-pipe communicating with the uppermost pipe of the first section or coil A, 50 and by which the ammonia-gas is admitted to the condenser.

F is an outlet-pipe for the liquid ammonia, said pipe having a pipe-connection f with the lowermost pipe of each section or coil.

G are the usual water-tanks, from which the 55 water is discharged so as to trickle down over the surface of the condenser-pipes.

The ammonia, in the form of gas, is forced in through the pipe E to the uppermost pipe of the first section or coil A, and, passing 60 downwardly through the pipes of said section or coil, is gradually cooled and condensed by the water trickling down over the surface of the pipes. The liquefied ammonia, collecting in the lower portion of the first section 65 or coil, passes off through the outlet-pipe F. The gaseous ammonia then passes upwardly through the connecting-pipe A' to the top of the second section or coil and down again through it, the pipes being subjected to the 70 cooling action of a fresh supply of water trickling over the surface of the pipes. From the bottom of this section or coil the condensed or liquid ammonia passes off, while the gas again passes upwardly through the connecting-pipe B' to the third section or coil, and 75 so on.

In the ordinary form of condensers the sections or coils are entirely separate, having no connection whatever, and the inlet by which 80 the gas is supplied communicates with the top of each section or coil, so that in fact each row is a mere duplicate of the other. In my invention there are two objects sought to be obtained—viz., first, the saving of water, and, 85 second, the reduction of the ammonia-pressure. The first object is obtained by subjecting the ammonia-gas to the condensing or liquefying action of successive flows of water, so that being partially cooled in the first 90 section or coil it is then subjected to the action of a fresh supply of cold water in the second section or coil and is further cooled, and so on.

Now, in the ordinary form where the sections or coils of pipes are wholly disconnected and the ammonia-gas is forced into each one, it is apparent that when as much of the gas is liquefied as is possible the cooling-water itself has its temperature raised so high as 100 to become of no effect, and therefore it requires a larger amount of water to be used

to accomplish the necessary result; but by passing the gas through the several sections successively, as I have described, and using water on each section, a much less amount of 5 water need be used in order to liquefy the ammonia.

The second object is attained by reason of an increased area within the pipes, which can be utilized by the ammonia in the form of 10 gas. Where each section or coil is separate there is about an equal amount of liquid ammonia accumulated in the lower portion of each section, thus confining the gas to the upper portion and reducing the available area 15 and increasing the pressure of the gas; but in my construction the larger portion of the liquid ammonia is in the first section or coil and is carried off by the outlet-pipe F, while in the succeeding sections or coils the amount 20 of liquid ammonia is very much reduced, thereby affording a greater area for the gas, which materially reduces the pressure.

Having thus described my invention, what I claim as new, and desire to secure by Letters Patent, is—

25

In an ice-machine, the ammonia-condenser consisting of separate sections or coils of pipes, a pipe-connection between the lowermost pipe of each section or coil and the uppermost pipe of the succeeding section or 30 coil, an inlet-pipe for the ammonia-gas communicating with the uppermost pipe of the first section or coil, and an outlet-pipe communicating with the bottom pipe of each section or coil, substantially as herein described. 35

In testimony whereof I have hereunto set my hand.

PAUL STECK.
